ISRAEL I. RICHARDSON, OF DELAWARE, OHIO.

Letters Patent No. 63,098, dated March 19, 1867.

IMPROVEMENT IN FIRE-PLACES.

The Schedule referred to in these Letters Patent and making part of the same.

TO ALL WHOM IT MAY CONCERN:

Be it known that I, ISRAEL I. RICHARDSON, of Delaware, in the county of Delaware, and State of Ohio, have invented a new and improved Fire-Place; and I do hereby declare the following to be a full, clear, and exact description of the same, sufficient to enable one skilled in the art to which the invention appertains to make use of it, reference being had to the accompanying drawings, forming part of this specification, and in which my invention is represented by elevations.

The grate occupies the ordinary position, and upon the sides, occupying recesses in the jamb, are chambers, through which the flues from the grate are conducted. The chambers are closed in front by perforated ornamental doors, through which the heat passes to the room. At the lower bend of the flues are ash-pans, to collect the dust which blows over, and the flues, after radiating heat in the chambers, discharge into the chimney above the grate ceiling.

In the drawings, A is the grate; B the ash-pit; C the fender. The grate may be set as usual, with its front flush with the face of the chimney wall; but instead of discharging backward and upward into the chimney flues D on each side, lead from points beneath the ceiling of the grate and pass into chambers, E, on each side. The chambers E, by preference, have bright metal back walls, so as to radiate the heat towards the front, where it passes through the perforations or ornamental openings in the doors F F into the rooms. The flues D pass into a chamber, G, wherein is an ash-box, M, to collect dust and ashes, and thence recurring upward, they reach a coupling, H, where they unite, and together discharge their contents into the chimney.

The grate thus constructed, with auxiliary air-heating chambers, is capable of as much neatness and ornamental appearance as the usual and favorite grate, and thus much of the economy of the stove and radiator is attained without the unsightliness and inconvenience of the stove, which occupies so much room and is in some other respects so undesirable and unpopular in fine parlors. The radiating and heating power of the apparatus thus constructed is much greater than that of the grate alone, as so much of the heat which would otherwise pass up the chimney is, by means of my arrangement, imparted to the air in the chambers E E, from whence it passes through the perforations in the door into the room.

Having described my invention, what I claim as new, and desire to secure by Letters Patent, is—

I claim the arrangement of the open grate A, chambers E, recessed in the jamb, and with perforated front doors and reverberating flues D D, as described and represented.

ISRAEL I. RICHARDSON.
